[57] CLAIM

The ornamental design for an extension for a light switch actuator, as shown and described.

DESCRIPTION

FIG. 1 is a front and lower right perspective view of an extension for a light switch actuator showing my new design. The broken line showing of the switch face plate is included for the purpose of illustrating environmental elements only and forms no part of the claimed design; FIG. 2 is a left side elevational view an extension for a light switch actuator showing my new design on a slightly reduced scale, the right side elevational view thereof being a mirror image; FIG. 3 is a rear elevational view thereof; FIG. 4 is a top plan view thereof; and, FIG. 5 is a bottom plan view thereof.
